(57) **CLAIM**

The ornamental design for a medical gown, as shown and described.

DESCRIPTION

The present application is a divisional application of U.S. Design patent application Ser. No. 29/647,539, filed May 14, 2018, the entire contents of which are incorporated herein by reference in its entirety.

FIG. 1 is a front perspective view of a medical gown;

FIG. 2 is a front elevational view thereof;

FIG. 3 is rear elevational view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

The broken lines shown illustrate portions of the medical gown that form no part of the claimed design.

1 Claim, 6 Drawing Sheets
